UNITED STATES PATENT OFFICE.

ALFRED B. EVANS, OF PHILADELPHIA, PENNSYLVANIA.

DESIGN FOR A PITCHER OR SIMILAR ARTICLE.

SPECIFICATION forming part of Design No. 25,122, dated February 4, 1896.

Application filed September 21, 1895. Serial No. 563,268. Term of patent 3½ years.

To all whom it may concern:

Be it known that I, ALFRED B. EVANS, a citizen of the United States, residing at No. 10 South Fortieth street, in the city and county of Philadelphia, in the State of Pennsylvania, have invented and produced a new and original Design for a Pitcher or Similar Article of Manufacture, of which the following is a specification, reference being had to the accompanying drawing.

The drawing is a perspective view of a pitcher or similar article of manufacture, showing my design.

The leading feature of the design is a reduced full-length figure of a man, intended to suggest the Emperor Napoleon I, the proportions of the different parts of the figure and the articles of clothing being so designed as to be adapted to be worked into or placed or impressed upon a pitcher or similar article.

The entire design, as shown by the drawing herewith submitted, for a pitcher or similar article, consists of the full-length figure of a man, reduced, and either in relief or on the surface glaze showing the full face, sides and back of the head, except as concealed by the high cloak-collar and the chapeau, all of which are hereinafter more fully described. The figure is dressed in a sort of four-cornered chapeau, high boots, a military cutaway coat, showing the lower portion of the vest, on the

coat being a cross as a decoration, while depending from the shoulders and reaching to the foot or base of the pitcher or similar article is a cloak which conceals the sides and back of the body of figure entirely, the shoulders, left arm, and sides and back of the neck. 35

The design represents a man in a standing posture with the left hand entirely concealed under the cloak, with the right arm bent and 40 the fingers thereof thrust into the coat, while the cloak, thrown open, hangs from the shoulders so as to show the entire front view of the figure except a small portion of the shoulders and the entire left arm. 45

The front of the figure forms the front of the pitcher or similar article, the cloak forms the sides and back of the bowl thereof, the sides and back of the head and the cloak-collar form the sides and back of the neck of the 50 pitcher, and the chapeau, the crown or top thereof being open, forms the top or rim thereof. The feet and cloak of the figure rest on the foot or base of the pitcher. 55

What I claim is—

The design for a pitcher or similar article as herein shown and described.

ALFRED B. EVANS.
